CLAIM

The ornamental design for a gaming machine with graphical user interface as shown and described.

DESCRIPTION

FIG. 1 is a front perspective view of a gaming machine with graphical user interface showing our new design; FIG. 2 is a front perspective view thereof with the shading on the screen omitted for clarity purposes;

FIG. 3 is a front view thereof;

FIG. 4 is a right view thereof;

FIG. 5 is a rear side view thereof;

FIG. 6 is a left side view thereof;

FIG. 7 is a top view thereof; and,

FIG. 8 is a cross-section view thereof taken through line 8-8 of FIG. 7.

The broken lines depicting the remainder of the gaming machine illustrate environmental structure and form no part of the claimed design. The curved oblique line shading shows that the surface is a transparent, translucent, highly polished or reflective surface.
